NONSKID PLASTIC WOODCUTTER'S WEDGE

Gerald R. Bedard, 419 Campbell St., Manchester, N.H. 03103, and Donald Oleniak, Squamscott Road, Strat-
ham, N.H. 03885

Filed Dec. 13, 1974, Ser. No. 532,291

Term of patent 14 years

Int. Cl. D8—03

U.S. Cl. D8—47

FIG. 1 is a perspective view of a nonskid plastic woodcutter's wedge showing our new design;

FIG. 2 is a front elevational view;

FIG. 3 is a rear elevational view;

FIG. 4 is a right side elevational view;

FIG. 5 is a top plan view; and

FIG. 6 is a bottom plan view thereof.

We claim:

The ornamental design of a nonskid plastic woodcutter's wedge, as shown.
